UNITED STATES PATENT OFFICE.

ARISTOTLE J. ANTIPAS, OF PASADENA, CALIFORNIA.

FOLDABLE CAMP CHAIR.

Application filed January 19, 1926. Serial No. 82,204.

My invention is a folding camp chair of the type having a folding back and a fabric seat.

An object of my invention is the construction of a folding camp chair having a folding back, adapted to fold closely against the folded legs of the chair when the chair is in folded position and having braces to hold the back in folded position and to support the back when the chair is extended or unfolded for use.

Another object of my invention is to utilize cross rods as strengtheners which also are utilized to take the stresses directly coming on the canvas seat.

In my camp chair I utilize folding legs of substantially the ordinary type; a folding back is hinged to the upper ends of a pair of legs; a diagonal brace is connected between the back and one of the legs, being detachable from the leg, the back is arranged to hinge forwardly so that when the legs are folded together, the back folds down over the legs and the brace swivelled into a reverse position in regard to the back, and engaging the legs to hold the back and legs clamped firmly in a folded position.

My invention will be more readily understood from the following description and drawings, in which:

Figure 1 is a perspective view of my camp chair.

Fig. 2 is a front elevation of the chair taken in the direction of the arrow 2 of Fig. 3.

Fig. 3 is a side view of the chair taken in the direction of the arrow 3 of Fig. 2.

Fig. 4 is a vertical section on the line 4—4 of Fig. 2.

Fig. 5 is a front view of the folded chair taken in the direction of the arrow 5 of Fig. 6.

Fig. 6 is an edge view of the folded chair taken in the direction of the arrow 6 of Fig. 5.

Fig. 7 is an alternative construction of chair in which the braces connecting the leg and the back are jointed.

The main construction of my chair is illustrated particularly in Figs. 1 to 4, having outer legs 1 and inner legs 2 crossed over each other and connected by a pivot rod 3 which extends through the legs at opposite sides of the chair. The outer legs have a bevelled end 4 at the upper part of the legs, adapted to form an angle with the bevelled

end 5 of the side posts 6 of the back 7; these posts being connected to the legs 1 by hinges 8. The posts of the back are joined by an upper bar 9 and a metal bar 10.

A seat 11 is formed by an upper and lower strip of canvas 12 and 13. This canvas is preferably secured to a cross rod 14 cut square on the back to rest against the upper ends of the inner legs 2, passing around a slat 15 which is secured to the upper ends of the outer legs 1. This slat is notched at each end so as to extend outwardly over the legs 1 as indicated by the numeral 16 and to extend partly inwardly of said legs; the inner edge of the slat fitting close against a cross rod 17 which is riveted to the upper parts of the legs 1. A cross rod 18 is also connected between the upper ends of the legs 2 behind the cross rod 14. The canvas of the seat passes over the curved edge of the cross rod 14, loops over the slat 15 and the rod 17 and extends upwardly over the rod 18 between said rod and the cross rod 14.

The back is braced to the legs by a pair of braces 19 which at their upper ends are swivelled to the side posts 6 by pivot pins 20. These braces have hooks 21 formed at their other end adapted to engage over pins 22 in the legs 1 to hold the side posts and hence the back in the proper position when extended, as clearly indicated in Figs. 1, 3 and 4.

Additional cross bracing of the legs is provided by the cross slat 23 between the lower ends of the legs 1 and the rod 24 between the lower ends of the inner legs 2.

When it is desired to fold the chair, the braces 19 are unhooked from the pins 22, the legs are pressed together so that the seat droops down between the legs, the back is hinged forwardly over the legs, hanging down into the position shown in Fig. 6, and the braces 19 are swivelled on the pins 20 into a reverse position so that the hooks may engage pins 25 on the lower ends of the legs 1; thus securely clamping the back in its downwardly folded position and preventing the legs from folding.

My form of braced back may be used with a type of chair having a rigid seat such as a wooden seat, pivoted to either set of the legs and adapted to hang downwardly when the chair is folded, the braces 19 holding the back in the proper position for use and the back and legs clamped together when folded.

I preferably use a jointed cross brace 26

secured to the upper end of the legs 1 and 2 by means of pins or the like and having a pivotal connection 27, thereby allowing the braces to be folded, and in the open position as shown in Figs. 1, 3 and 4 holding the chair with the legs rigidly spread apart.

In Fig. 7 the brace 28 connecting the side posts 6 and the legs 1 is jointed, having a connecting pin 29 between the upper and lower section of the brace and having both ends of the brace secured to pins 30. In this type of brace a person sitting back on the chair forces the brace into proper position.

It will thus be seen that although my chair is of a simple design, nevertheless the construction may be considerably changed in general features and specific details to adapt it to different styles of chairs. Such changes would be within the spirit of my invention as set forth in the description, drawings and claims.

Having described my invention, what I claim is:

1. A folding camp chair comprising in combination outer and inner legs crossed over each other and pivoted together, a back having side posts pivotally connected to the upper ends of the outer legs, a pair of braces

pivotaly connected to the side posts and having hooked ends, pins on the outer legs 30 to cooperate with the said hooks, and a second set of pins adjacent the lower ends of the outer legs to engage the brace bars when the back and legs are folded.

2. A folding camp chair comprising in combination outer and inner legs crossed over each other and pivoted together, a back hinged to one set of legs, a slat connecting said legs adjacent the hinge, a metal rod secured between the said legs immediately behind the said slat, a cross rod connecting the upper ends of the other legs, a seat formed of fabric encircling the said cross rod, the slat and the metal rod, braces pivotally connected to the back, pins on the legs to which the back is hinged, hooks on the braces adapted to engage said pins to support the back in extended position, and a second set of pins adjacent the lower ends of the legs to which the back is hinged, adapted to engage the brace to hold the seat and the legs in folded position.

In testimony whereof I have signed my name to this specification.

ARISTOTLE J. ANTIPAS.
